UNITED STATES PATENT OFFICE.

CORNELIS MEDENDORP, OF GRAND RAPIDS, MICHIGAN.

PAD-HOLDER.

953,631.

Specification of Letters Patent. Patented Mar. 29, 1910.

Application filed April 6, 1909. Serial No. 488,186.

To all whom it may concern:

Be it known that I, CORNELIS MEDENDORP, a citizen of the United States of America, residing at Grand Rapids, in the county 5 of Kent and State of Michigan, have invented certain new and useful Improvements in Pad-Holders; and I do hereby declare the following to be a full, clear, and exact description of the invention, such as 10 will enable others skilled in the art to which it appertains to make and use the same.

My invention relates to improvements in pad holders, and more particularly to holders for writing pads, and its object is to 15 provide convenient means for opening the clamp thereof, and to provide the device with various new and useful features hereinafter more fully described and particularly pointed out in the claims; reference 20 being had to the accompanying drawings, in which:

Figure 1 is a perspective of a device embodying my invention; Fig. 2 an enlarged plan view of a portion of the same; and, 25 Fig. 3 a side view of the same, still further enlarged and with parts broken away.

Like numbers refer to like parts in all of the figures.

1 represents the board or bed plate of the 30 device. 2 a clamp having lugs 3 turned down and fixed in any convenient manner upon a shaft 4, so as to be nonrotative thereon. Around this shaft is a spring 5 having one end engaging the bed plate, and 35 the other end engaging one of the lugs 3, whereby the clamp is caused to yieldingly grip the pad in the usual manner. This shaft 4 is journaled in hangers 10 mounted on the bed plate, and my invention consists 40 mainly in the means whereby this clamp may be opened more conveniently than by the usual method of depressing its upper end, for which purpose the shaft 4 is prolonged to a point near the corner of the 45 bed plate and thence bent rearward as at 6 forming a crank arm and thence extended upward as at 6^a terminating in a push button 7 to manually depress the arm, and thus

rotate the shaft and open up the clamp member 2. The crank member is inclosed 50 in a casing 8 having a recess 9 to receive and journal the shaft, and also provided with an opening 11, through which the upwardly extended portion 6^a extends. This case is also provided with lugs 12, whereby it is 55 attached to the plate 1 and has a projection 13 with which the fingers of the operator are engaged when the push button 7 is depressed by the thumb. Beneath the crank arm 6 is a spring 14 within the case which 60 tends to raise the crank arm, and thus assist in yieldingly closing the clamp 2 upon the pad.

What I claim is:

1. A pad holder, comprising a bed plate, 65 hangers mounted on the bed plate, a shaft journaled in the hangers and extended to near the side of the bed plate, a clamp member supported on the shaft by lugs non-rotative on the shaft, a crank arm on 70 the end of the shaft and extended rearward and thence upward, a casing having a recess to receive the crank arm and an opening through which the upward extension projects, a push button on said extension, and 75 a spring to yieldingly force the clamp member toward the bed plate.

2. A pad holder, comprising a bed plate, a shaft journaled in hangers mounted on the bed plate, a clamp member mounted on the 80 shaft and rotative therewith, a spring to yieldingly force the clamp member toward the bed plate, a crank member extending rearward from one end of the shaft, an upward extension on the crank member, a case 85 inclosing the crank member and having an opening through which the said extension projects, and a rearward projection on the case.

In testimony whereof I affix my signature in presence of two witnesses.

CORNELIS MEDENDORP.
